APPARATUS FOR PACKAGING ARTICLES

Glenn L. Anderson, Cleveland Heights, Ohio

Application February 16, 1939, Serial No. 256,820

14 Claims. (Cl. 226—18)

This invention relates to apparatus for packaging articles, more particularly to apparatus for enclosing in a container a predetermined number of articles, the apparatus involving a mechanism which automatically operates to control each packaging operation when the predetermined number of articles have been delivered to the apparatus. The term container, as used herein, has reference to an enclosure of any desired form and constructed of any suitable material, but arranged to provide an opening to receive the articles, the disclosed construction of container consisting of a paper bag. The articles to be packaged are shown as consisting of sections of textile material, such as napkins and towels, as well as other articles which when flat or folded are of substantially uniform size and shape so as to be stacked and bodily inserted into a container.

The apparatus herein disclosed and embodying my invention is adapted for use where a large number of articles of the type above referred to are laundered, such as concerns for supplying linen, as well as laundries, clubs, hotels, hospitals, camps, etc.

One object of the invention is to provide an improved apparatus of this type having a movable receiver for the articles and means to control the operation thereof when filled with a batch of articles, whereby each batch is delivered into a container.

Another object of the invention is to provide an improved machine of this type wherein the articles are packaged in batches with minimum labor, thereby insuring a substantial saving over present practice.

Another object of the invention is to provide an improved apparatus of this type which is relatively simple and easily operated to package batches of articles in a rapid manner.

Other objects of the invention will be apparent to those skilled in the art to which my invention relates from the following description taken in connection with the accompanying drawings, wherein

Fig. 1 is a side elevation, partly in section on the line 1—1 of Fig. 2, of an apparatus embodying my invention.

Fig. 2 is a section on the line 2—2 of Fig. 1.

Fig. 3 is a fragmentary view (enlarged) of Fig. 2, parts being broken away.

Fig. 4 is a fragmentary side view of the receiver or stacker.

Figs. 5 and 6 are sections on the lines 5—5 and 6—6, respectively, of Fig. 4.

Fig. 7 is a fragmentary section on the line 1—1 of Fig. 2 (enlarged).

Figs. 7a, 8, 9 and 10, are sections on the lines 1a—1a, 8—8, 9—9 and 10—10, respectively, of Fig. 7.

Fig. 11 is a section on the line 11—11 of Fig. 12.

Fig. 12 is a section on the line 12—12 of Fig. 11.

Fig. 13 is a fragmentary view, partly in section, of one of the switches, and illustrating the manner of operating it.

Fig. 14 is a diagram.

Fig. 15 is a diagram showing a modification.

In the drawings, 1 indicates as an entirety a support preferably comprising a platform 1a mounted on legs 1b. The platform 1a supports a receiver or stacker 2 for the article to be packaged in containers, one of which is shown at 3. I have applied my invention to packaging textile articles and show for illustrative purposes only towels A in folded conditions. The bottom of the receiver is pivoted or hinged to the platform 1a on a transverse axis disposed at a point beyond its center remote its discharge end, so that the receiver normally tends to swing about

its pivot from its normal or receiving position (Figs. 1, 2, 3 and 7), to its discharging position, as shown in dotted lines in Fig. 1. The pivot for the receiver 2 is preferably arranged at the rear edge of the platform 1a so that the area rearward of the support 1 may be utilized by the operator to apply the empty container 3 to the receiver 2 and handle the filled containers in an easy and rapid manner. However, since the filled containers may be permitted to automatically disengage the receiver 2, they may drop

onto a conveyor or into a chute (not shown) and be conducted to a distant point. The pivot for the receiver 2 consists of a plate 4 fixed to the rear side wall of the platform 1a and a plate 4a (the plates having suitable knuckles connected by a pivot 4') arranged to support the receiver 2 in normal position, substantially horizontally with its front end lying over the platform 1a, whereby such end may releasably engage a catch mechanism indicated as an entirety at 5. The side edges of the plate 4a are inclined so as to converge toward the pivot 4' and are adapted to engage correspondingly arranged guides 6 on the bottom of the receiver 2, whereby the receiver 2 may be removed and another substituted dependent upon the size of the articles A to be stacked therein and packaged and the height of the stack according to the number to be filled in each container. Suitable means may be pro-

vided to hold the receiver 2 in the normal position when the catch mechanism 5 is released. The receiver 2 is provided with a bottom edge 7 which is inclined so as to facilitate the removal of the articles A from the receiver 2.

When the receiver 2 is pivoted to its discharging position, the articles A are delivered from the receiver 2 into the container 3. The receiver 2 is pivoted to its receiving position by the action of a spring 8 which is connected to the receiver 2 and the platform 1a. The receiver 2 is held in its receiving position by the catch mechanism 5.

The receiver 2 is provided with a bottom edge 7 which is inclined so as to facilitate the removal of the articles A from the receiver 2.

When the receiver 2 is pivoted to its discharging position, the articles A are delivered from the receiver 2 into the container 3. The receiver 2 is pivoted to its receiving position by the action of a spring 8 which is connected to the receiver 2 and the platform 1a. The receiver 2 is held in its receiving position by the catch mechanism 5.

vided for removably securing the bottom of the receiver to the plate 4a, the illustrated means shown consisting of an embossment 7 on the receiver bottom arranged to lie back of the plate knuckles (see Fig. 7), the resiliency of the metal permitting the embossment to ride the knuckles and plate 4a when positioning the receiver thereon or removing it therefrom.

The receiver 2 consists of a bottom and side walls 2a, being open at its discharge end to permit the towels A to slide therethrough into a container 3, open at its top from end to end and open at its opposite end. The towels A may be positioned in or delivered to the receiver at either side or at the end opposite to the discharge end, but in the arrangement shown, I deliver the towels from one side, as later set forth.

8 indicates spring clips mounted on the sides 2a of the receiver and arranged to removably receive between them and the side walls 2a the open end portion of a container 3, which is of a size to readily fit over the discharge end of the receiver 2 and a presser 9 (later referred to), the clips 8 permitting the container to be readily attached in position as shown in Fig. 1 and to be removed therefrom. By preference I provide on the receiver 2 a supplemental holder 10 for the container 3 shaped to form a rest for the container to hold it in extended position when attached to the receiver (see Fig. 1) and engage the bottom of the container to support it when filled and the receiver swings downwardly as shown in dotted lines in Fig. 1, this arrangement permitting the filled container to be readily disengaged from the receiver 2, and then closed and sealed in any desired manner.

The towels A are placed in the receiver, one at a time, whereby they may be counted, each such operation serving through a control mechanism indicated as an entirety at 11, to operate an index mechanism indicated as an entirety at 12, so that when a predetermined number of towels, according to the pre-setting of the mechanism 12, has been positioned in the receiver 2, the index mechanism 12 operates the catch mechanism 5 to release the receiver 2, the weight of the discharge end of the receiver 2, supplemented by the weight of that portion of the towels adjacent such end, serving to effect operation of the receiver to dumping position as shown in dotted lines.

The presser 9 is mounted at the discharge end of the receiver 2 and consists of a plate extending across and normally resting on the tops of the side walls 2a and having depending end members 9a slidably engaging the outer surfaces of the side walls 2a. The side walls 2a are preferably embossed to form vertical guides and the end members are correspondingly shaped to loosely fit these embossments to guide the presser 9 upwardly and downwardly. The inner edge of the presser 9 is provided with an upwardly inclined flange 9b which serves to guide the adjacent end of the stacked towels below the presser 9, the weight of the latter serving to compress the towels together as they slide from the receiver 2 into the container 3 and thus maintain them in stacked relation during such movement. The side walls 2a are formed with openings 2b and a section of the wall forming each end member 9a is stamped out and bent laterally inwardly at 9b' so as to project into the adjacent opening 2b, the upper end wall of the

latter serving to limit the movement of the presser upwardly.

The control mechanism 11, in the form of construction shown in Figs. 1, 2, 3 and 14, comprises an electric switch 11a for closing an electric circuit 11' (see Fig. 14) and a device 13 for operating the switch 11a, which device has a portion 13a disposed in the path of movement of each towel A and is engaged and moved thereby to operate the switch when each towel is positioned in the receiver 2, as shown in Figs. 2 and 3, whereby the circuit 11' is closed each time a towel is positioned in the receiver 2. It will be noted that the apparatus herein disclosed may be incorporated in or associated with the discharge means of a power driven folding machine, whereby the towels or other articles will be supplied to the receiver automatically, but in the present disclosure and as built by me, it is intended to manually deliver the towels thereto. In this arrangement the switch 11a is mounted on a bracket 14 carried by the support 1, above and in spaced relation to one side wall 2a of the receiver 2, so as to form a delivery opening between the switch and the top of the adjacent side wall 2a and provide for the mounting of the operating device 13 in operative relation to the switch 11a, with its towel engaging portion extending across the delivery opening. The switch 11a comprises an insulating block 15 suitably fixed to the bracket 14 and supporting terminals 16, 16a, electrically connected to leads 17, 17a, respectively. As shown in Fig. 14, the lead 17a is connected to a lead 17x and the latter lead and the lead 17 are connected to the supply mains 17x'. Each terminal 16, 16a, is electrically connected to conductor strips 18, 18a, respectively, formed of resilient metal, the end portions of which are related so as to make and break the circuit 11'. The strip 18, which engages intermediate its ends an abutment 19 fixedly mounted in the block 15, is shaped so that its free end is normally out of contact with the strip 18a (see Fig. 3). The strips 18, 18a, and outer ends of the terminals are enclosed by a cover 20 (suitably secured in position) which is formed with an opening to slidably support a plunger 21, the plunger being positioned to engage the conductor strip 18 between the terminal 16 and abutment 19, and when the plunger 21 is pushed inwardly by operation of the device 13, it flexes the strip 18 between the terminal 16 and abutment 19 and causes its outer end portion to swing laterally into engagement with the strip 18a, thereby closing the circuit 11'. Upon release of pressure on the plunger 21, the strip 18 springs back to normal position, breaking the circuit 11' and pushing the plunger outwardly, such outward movement being limited by the head on the inner end of the plunger engaging the cover 20. The operating device 13 consists of a lever, substantially of bell-crank shape, one arm 13a of which (already referred to) extends across the opening for the towels and the other arm 13b of which is arranged to engage with the outer end of the plunger 21 and project it inwardly to operate the strip 18 and close the switch 11a, as above set forth. The lever 13 is formed of resilient material so that in the event the lever is moved an undue distance by the operation of positioning a towel in the receiver 2, the arm 13b will yield after it engages the cover 20. The lever 13 is pivoted on the bracket 14 below the switch 11a and its arms are so related that the arm 13a serves as a weight to swing

or return the lever to normal or operative position after each towel A has been delivered to the receiver 2, the return movement of the lever being limited at a predetermined position by a tail member 13c extending rearwardly from the lever and arranged to engage a stop 22 provided on the bracket 14.

The index mechanism 12 comprises a ratchet mechanism, preferably consisting of a ratchet 23 of circular or disk form having a predetermined number of teeth (which may be provided on its periphery) and a pawl 24 arranged to rotate the ratchet the distance of one tooth for each operation of the pawl, the pawl being operated by the closing of the circuit 11', as later set forth, so that each time a towel A is positioned in the receiver 2, the ratchet disk 23 is moved the distance of one tooth. The ratchet disk 23 is connected by a lead 23' to the lead 11x and operates, when rotated a predetermined distance to close an operating circuit 25', which effects operation of the catch mechanism 5, as later set forth, to release the receiver 2. Accordingly when a predetermined number of towels A have been positioned in the receiver 2, it is released and the towels therein slide into the container 3, as already described. The electric connections between the ratchet disk 23 and a lead 25a, which is connected to the lead 11, are so arranged that the circuit 25' may be closed after the disk has been rotated different angular distances, so that by means of a pre-setting switch 26 in the circuit 25' the receiver 2 will be released each time the number of towels, as determined by the switch 26, has been positioned therein. In the arrangement illustrated, the ratchet disk 23 is provided with 100 teeth and opposite one tooth, which may be considered the 100th tooth, I provide a contact 27; and equally spaced around the disk 23 I provide four stationary contacts 28, 29, 30 and 31 each arranged to be engaged by the contact 27 as the disk rotates. The pre-setting switch 26 is provided with an arm 32 connected to the lead 25a and arranged in one position (represented by the number "25") to engage a terminal 33 to connect it to the lead 25a and in another position (represented by the number "50") to disconnect the terminal from the lead 25a. As shown, a lead 34 connects the contacts 29 and 31 to the lead 25a and leads 35, 35a, connect the contacts 28, 30, to the terminal 33. With the switch arm 32 in engagement with terminal 33, it will be seen from the foregoing description that each time the disk 23 is moved the angular distance of 25 teeth by the successive operations of the pawl 24, the contact 27 will engage one of the contacts 28, 29, 30 and 31, and close the circuit 25' and effect a release of the receiver 2 (as later set forth) and this operation will be repeated each time the contact 27 engages any one of said contacts, whereas if the switch arm 32 is disengaged from the terminal 33, the contact 27 will close the circuit 25' only when it engages either contacts 29 and 31. It will thus be seen that the indexing mechanism 12 may be set to cause a discharge of the receiver each time 25 towels are positioned therein or each time 50 towels are positioned therein; but by providing a larger or lesser number of contacts around the disk 23, the receiver can be controlled when filled with any desired number of towels.

The ratchet disk 23 is rotatably mounted on an internally threaded hollow bushing 23a which is formed of conducting material and fits an

opening in a block 23b formed of insulating material, the block being suitably fixed to the base plate of a casing 23c. The opening for the bushing 23a is enlarged at its inner end so that the head of a bolt 23d, which is threaded into and through the bushing 23a, may be countersunk within the block and co-act with a flange on the bushing which engages with the inner face of the block 23b, to secure the bushing in position thereon. The inner end of the bushing 23a is externally threaded to take a nut 23e which holds in place on the bushing a washer 23f to support the disk 23 between it and the bushing flange. A cross member 23g extends over the disk 23 and is supported at its opposite ends on the block 23b. The cross member 23g engages the inner end of the bolt 23d and is connected at one end to the wire or lead 23', as shown in Fig. 11, whereby the disk 23 is electrically connected through the bushing 23a, bolt 23d and cross member 23g to the lead 23'. The contact 27 is shown in Fig. 12 as consisting of a hollow member 23h containing a ball and a spring which tends to project the ball outwardly and ride the inner face of the block 23b as the disk 23 rotates, the contacts 28, 29, 30 and 31 being countersunk in the block 23b in position to be engaged by the ball of the contact 27.

The pawl 24 consists of a main element 24a suitably pivoted on the block 23b and a separate element 24b pivoted on the main element 24a and normally maintained in engagement with the teeth of the disk 23 by a spring 24c connected to the elements 24a, 24b, this construction serving to insure accurate engagement with the successive ratchet teeth to move the disk the distance of one tooth with each operation of the main element 24a. The outer end of the pawl element 24a is connected to the outer end of a thrust member 36, the inner end portion of which forms the core of a solenoid 37. As will be understood from Fig. 14, the coil of the solenoid 37 is connected in series in the circuit 11' (being interposed in the lead 11a), so that each time the switch 11a is operated to close the circuit 11', the coil of the solenoid is energized and moves the thrust member toward the left, as shown in Figs. 11 and 14, to operate the pawl 24. A spring 38 coiled around the thrust member 36 and interposed between a collar 38a thereon and the inner end walls of the casing for the solenoid coil, serves to move the thrust member 36 in the opposite direction, upon de-energizing of the solenoid coil, and to position the pawl 24 behind the succeeding ratchet tooth ready for the next operation.

As will be apparent from the foregoing description, each time the operating circuit 25' is closed, the catch mechanism 5 is operated to release the receiver 2, such operation of the catch mechanism being effected by a solenoid 39, the coil of which is connected in series in the circuit 25' (that is, in lead 25a). The bottom wall of the receiver at its inner end is provided with a section 40 depending through an opening 1b' formed in the platform 1a and carrying at its lower end an outwardly extending shoulder 41 with which the lock and release element 5a of the catch mechanism 5 engages to releasably lock the receiver 2 in normal position for filling. The catch mechanism 5 comprises a shaft 42 mounted at its opposite ends on the spaced arms 43 of a bracket 43a, the lock and release element 5a (already referred to) being rotatably mounted on the shaft 42 and an element 5b pivoted at

one end of the shaft 42 for controlling the operation of the element 5a to lock or release the shoulder 41. The lock and release element 5a is enlarged at one side to form a wall 5a' extending substantially radially and arranged to engage the shoulder 41 to lock the receiver 2 in normal position (see Fig. 7) and provided at another side with a lug 5a'', normally engaging a stop 5b' on the controlling element 5b. The controlling element 5b is shaped at its inner end 10 to provide spaced hollow bosses 5x through which the shaft 42 extends and disposed on opposite sides of the element 5a, the bosses being connected by a bar which forms the stop 5b'. The outer end portion of the element 5b is bifurcated to straddle a rod 44 below a head 44a on its outer end. The opposite end portion of the rod 44 forms the core of the solenoid 39, so that when the coil thereof is energized by the closing of the operating circuit 25', the rod 44 is moved 20 endwise downwardly and carries with it the element 5b thereby swinging the latter about the shaft 42; and when the element 5b is operated as just described, the stop 5b' swings with it to the position shown in dotted lines in Fig. 7, to 25 disengage the lug 5a'', so that the element 5a is then free to rotate about the shaft 42, to release the receiver 2. Accordingly, upon disengagement of the element 5b from the element 5a, the weight of the discharge end of the receiver 2 is effective to swing it to the discharge position, the shoulder 41 in such swinging movement serving to rotate the element 5a (counterclockwise as viewed in Fig. 7) and ride past the wall 5a' in opposition to a relatively light spring 5x', which 30 is connected to the element 5a and shaft 42 (see Fig. 7a) and normally tends to rotate the element clockwise. Upon de-energizing of the solenoid 39, a spring 45 coiled around the rod 44 and interposed between the bifurcations of the 40 element 5b and the casing for the solenoid coil, projects the rod 44 upwardly and swings the element 5b back to normal position.

Following the return of the element 5b to normal position, the receiver 2 may be positioned 45 for refilling and in the movement thereof to normal position, the shoulder 41 will ride the wall 5a', since the element 5a is free to rotate clockwise, and become locked below this wall.

It will be noticed that when the movable contact 27 engages any one of the stationary contacts 28, 29, 30, 31, (a) the receiver 2 is automatically released and swings to its discharging position, (b) that the movable contact 27 remains engaged with the adjacent stationary contact until the disk 23 is moved one step or one tooth and (c) that re-filling of the receiver cannot take place until it is returned to its normal position; and that if returned to normal position while the contact 27 is engaged with any of the stationary contacts, the circuit 25' will remain closed and maintain the coil of the solenoid 39 energized with the catch mechanism 5 in operated position, so that the receiver 2 cannot be secured and locked by the lock and release element 5a.

To permit the receiver to be returned to and locked in normal position and locked by the catch mechanism 5 while the movable contact 27 remains in engagement with any one of the stationary contacts 28, 29, 30 and 31 and also provide for the operation of the catch mechanism 5 when the movable contact engages the succeeding stationary contacts, I provide an auxiliary means, having a switch which is arranged

15 (a) to break the circuit 25' after the receiver 2 has been released by the catch mechanism (so that the coil of the solenoid 39 is de-energized) and (b) to be moved back to circuit closing position by the closing of the circuit 11' to rotate the ratchet disk 23 one tooth, due to the positioning of a towel in the receiver 2 (the first towel in the next refilling operation) and operation of the switch 11a.

20 The auxiliary means comprise the following: 46 indicates a solenoid mounted in a casing 46a suitably fixed to an upright 47, which is disposed at one side of the receiver 2 and forms part of the support 1. I preferably provide at the opposite side of the receiver an upright 47a, which forms a part of the support 1, and on the side walls 2a of the receiver I provide laterally projecting wings 2c which engage the uprights 47, 47a to limit the tilting of the receiver 2 at a predetermined position. The coil of the solenoid 46 is connected in series in the circuit 11' (being interposed in the lead 17, as shown in Fig. 14) and the core 46' thereof has connected to its front end a plunger 48 normally projecting beyond the casing 46a (see Fig. 13). At its rear end the solenoid core is provided with an extension 49 formed of Bakelite or other suitable insulating material and the outer end of the extension 49 is provided with a sleeve 50 formed of copper or other conducting material, which sleeve 50 engages a pair of resilient contacts 51, 51, connected to the lead 25a, as shown in Fig. 13. The contacts are mounted in a cap 46a' preferably screw threaded on the rear end of the casing 46a. As shown in Figs. 1 and 13, the plunger 48 projects beyond the upright 47 and is disposed in the path of movement of the adjacent wing 2c, so that when the receiver 2 is released from the catch mechanism 5 and tilts to its discharging position, the adjacent wing 2c engages with and moves the plunger 48, core of the solenoid 46, section 49 and sleeve 50 endwise, which operation moves the insulating section 49 into engagement with the contacts 51, 51, thereby breaking the circuit 25' across these contacts. Upon opening of the circuit 25', the coil of the solenoid 39 is de-energized and the spring 45 moves the rod 44 upwardly and swings the element 5b to normal position so that the receiver 2 may be re-positioned and locked ready to be re-filled with towels A. With the receiver 2 in normal position the plunger 48 and parts connected thereto may be moved back to their first position and connect the contacts 51, 51, through the sleeve 50. As the coil of the solenoid 46 is connected in series in the lead 17, the operation of positioning the first towel in the receiver 2 will operate the switch 11a to close the circuit 11', the effect of which is to energize the coil of the solenoid 46, the magnetic influence thus established serving to move the core of the solenoid and parts connected to it in that direction opposite to the direction in which it was moved by the plunger 48 when engaged by the adjacent wing 2c.

25 From the foregoing description it will be noted that the core of the solenoid 46 and parts carried thereby and contacts 51, 51, constitute a switch in the circuit 25' which switch in one position permits the circuit to be closed by the movable contact 27 to operate the catch mechanism 5 and in another position breaks the circuit so that the catch mechanism may be re-set, notwithstanding the engagement of the contact 27 with an adjacent stationary contact.

52 indicates a dog mounted on the block 23b and arranged to ride the ratchet teeth on the disk 23 and prevent rotation thereof in the direction opposite to that effected by the pawl 24, the dog being yieldingly held in operative position by a spring 52a.

The switch arm 32 of the pre-setting switch 26 is connected to a shaft 53 which is provided with an operating handle 53a.

As shown in the diagram (Fig. 14), the leads 17a and 23' are connected to the lead 17x which is connected to one supply main 17x' and the lead 25a is connected to the lead 17 which is connected to the other supply main 17x'. In this arrangement, all of the circuits may be disconnected from the current supply by a single switch 54 having an operating handle 54a.

Fig. 15 is a diagrammatic view of a portion of the diagram shown in Fig. 14, but illustrating a modification of the control mechanism for operating the indexing mechanism 12, wherein in place of the switch 11 I provide a photo-electric cell indicated as an entirety at 55 and receiving electric energy by means of leads connected to the mains 17x'. In this arrangement the leads 17, 17a for the circuit 11' are connected to contacts or terminals 16x arranged to be connected to close the circuit by the armature of an electro-magnet 55'. As shown, one side wall 2a' of the receiver has a lateral extension 2x provided with a lens 56 spaced from a second lens 56a to form between them a passage for the towels leading to the receiver. An electric light or bulb 57 (which is connected to the mains 17x') provides light rays through the lens 56, 56a, onto the bulb 55a of the cell 55, the rays being broken or intercepted by the movement of each towel through the towel passage, whereby the cell operates the electro-magnet 55' to close the circuit 11' across the contacts 16x; the effect of which, as set forth in connection with Figs. 1 to 14, is to operate the indexing mechanism 12.

The towels A may be delivered to the receiver one or more at a time, each delivery operation serving to close the switch 11a and operate the disk 23 of the indexing mechanism 12 one tooth. With the contacts 28, 29, 30 and 31 spaced as shown and with 100 teeth on the disk 23, and if it was desired to enclose 50 towels in each container, by engaging the arm of the pre-setting switch 26 with the terminal 33 and positioning two towels at a time into the receiver, the latter would be discharged each time the movable contact 27 engaged each of the stationary contacts.

Various means may be used to count the towels, for example, by registering the number of discharging operations of the receiver, by recording the revolutions of the disk 23 and by an electric counter connected in series in the circuit 11' or circuit 25', and operated each time such circuit is closed. The counting means for the towels are not shown.

To those skilled in the art to which my invention relates many changes in construction and widely differing embodiments and applications of the invention will suggest themselves without departing from the spirit and scope of the appended claims. My disclosures and the description herein are purely illustrative and are not intended to be in any sense limiting.

What I claim is:

1. In apparatus of the class described, the combination with a support, of a receiver in which textile articles to be packaged are successively positioned into stacked relation and 75

formed at one end with a discharge opening through which the stack of articles is bodily discharged, said receiver being pivotally mounted adjacent its opposite end on said support, whereby it normally tends to swing to its discharging position, means for locking said receiver in a predetermined position to receive the articles to be packaged, and means controlled by the delivery of each article into said receiver for releasing said locking means when a predetermined number of articles has been stacked in said receiver.

5 2. In apparatus of the class described, the combination with a support, of a receiver in which textile articles to be packaged are successively positioned into stacked relation and formed at one end with a discharge opening through which the stack of articles is bodily discharged, means carried by one or more walls of said receiver for removably supporting a container in operative relation to said opening, means for holding said receiver in a predetermined position to receive the articles to be packaged, means operated by the delivery of each article into said receiver and arranged to release said holding means when a predetermined number of articles has been stacked in said receiver, and means operated by the movement of said receiver to discharging position for 10 making said holding means inoperative.

15 3. An apparatus as claimed in claim 2 wherein the last mentioned means are re-set by the succeeding operation of said delivery operated means.

20 35. 4. In apparatus of the class described, the combination with a support, of a receiver open at its top to permit the successive positioning therein of textile articles into stacked relation and having at one end an opening through which the stack of articles is bodily discharged, means carried by one or more walls of said receiver for removably supporting a container in receiving relation to said discharge opening, said receiver being movably mounted on said support and arranged when in one position to receive the articles and movable to another position to effect discharge thereof in stacked relation by gravity into the container, releasable means for holding said receiver in position for receiving the 25 articles, an indexing mechanism, means controlled by said mechanism for operating said releasable means when a predetermined number of articles has been stacked in the receiver, and means operated by the delivery of each article 30 into said receiver for operating said indexing mechanism.

35 45. 5. In apparatus of the class described, the combination with a support, of a receiver trun- 40 nioned thereon adjacent one end and formed at its opposite end with a discharge opening, said receiver being arranged when in one position to permit textile articles to be stacked therein and swingable to another position to effect discharge of the stacked articles through said opening, 45 means for removably supporting a container on said receiver in operative relation to said opening, releasable means for holding said receiver in its receiving position, electrical means for operating said releasable means, a step-by-step 50 movable device arranged when moved a predetermined distance to operate said electrical means, and separate electrical means controlled by the delivery of each article to said receiver 55 to move said device one step.

55 60. 6. An apparatus as claimed in claim 5 wherein 65 70

70 75

the first mentioned electrical means includes an electrically operated device for operating said releasable means, a circuit and a plurality of stationary contacts, said device being provided with a contact arranged to engage each of said stationary contacts and a pre-setting switch arranged to connect into the circuit either one of said stationary contacts.

7. In apparatus of the class described, the combination with a support, of a receiver trunnioned thereon adjacent one end and formed at its opposite end with a discharge opening, said receiver being arranged when in one position to permit textile articles to be stacked therein and swingable to another position to effect discharge of the stacked articles through said opening, releasable means for holding said receiver in receiving position, a step-by-step movable index member provided with an operating element, and means controlled by said element for operating said releasable means, the last said means including spaced elements arranged to be successively engaged by the element on said index member, and means for at will making certain of the last mentioned elements inoperative.

8. In apparatus of the class described, the combination with a support, of a receiver trunnioned thereon and formed at one end with a discharge opening, said receiver being arranged when in one position to receive articles to be packaged and swingable to another position to effect discharge of the articles through said opening, releasable means for holding said receiver in receiving position, an electrically controlled device and a circuit therefor arranged to release and re-set said releasable means, an indexing mechanism for controlling the circuit for said device, a separate electrically controlled device for operating said indexing mechanism and a circuit for said separate device having a switch arranged to close said circuit by the positioning of each article into said receiver, a switch in the circuit for said first mentioned device and arranged to be moved in one direction by said receiver when the latter swings to its discharging position to break said circuit, and means operated by the closing of the circuit for said separate device for restoring said last mentioned switch to its first position.

9. In apparatus of the class described, the combination with a support, of a receiver trunnioned thereon and formed at one end with a discharge opening, said receiver being arranged when in one position to receive articles to be packaged and swingable to another position to effect discharge of the articles through said opening, a catch mechanism for holding said receiver in receiving position, an electrically controlled device and a circuit therefor arranged to release and re-set said catch mechanism, an indexing mechanism for controlling said circuit, a separate electrically controlled device for operating said indexing mechanism and a circuit for said separate device having a switch for closing said circuit by the positioning of an article in said receiver, and separate means for controlling the circuit for said first mentioned device, said separate means including a switch normally forming a part of said circuit and arranged to be moved to an inoperative position by said receiver when operated to discharging position, whereby the first mentioned device re-sets said catch mechanism, and arranged to be moved to its normal position by the closing of the circuit for said separate device.

10. In apparatus of the class described, the combination with a support, of a receiver trunnioned thereon adjacent one end and formed at its opposite end with a discharge opening, said receiver being arranged when in one position to permit textile articles to be stacked therein and swingable to another position to effect discharge of the stacked articles through said opening, a catch mechanism for releasably holding said receiver in receiving position, an electrically controlled device for operating said catch mechanism, a ratchet disk and a pawl for operating said disk step-by-step, a circuit for said device, including a contact carried by said disk and a plurality of contacts on said support in spaced relation about the path of movement of the contact on said disk and each arranged to be engaged by the contact on said disk to complete the circuit to said device whereby the latter releases said catch mechanism, and means controlled by the delivery of each article into said receiver for operating said pawl.

11. An apparatus as claimed in claim 10, wherein means are provided for disconnecting certain of the contacts on said support from the circuit for said device.

12. In apparatus of the class described, the combination with a support, of a receiver trunnioned thereon adjacent one end and formed at its opposite end with a discharge opening, said receiver being arranged when in one position to permit textile articles to be stacked therein and swingable to another position to effect discharge of the stacked articles through said opening, a catch mechanism for releasably holding said receiver in receiving position, an electrically controlled device for operating said catch mechanism, a ratchet disk and a pawl for operating said disk step-by-step, a circuit for said device, including a contact carried by said disk and a plurality of contacts on said support in spaced relation about the path of movement of the contact on said disk and each arranged to be engaged by the contact on said disk to complete the circuit to said device whereby the latter releases said catch mechanism, means controlled by the delivery of each article into said receiver for operating said pawl, and means for breaking the circuit closed by said contacts by the movement of said receiver to its discharge position, whereby the catch mechanism is re-set.

13. In apparatus of the class described, the combination with a support, of a receiver trunnioned thereon adjacent one end and formed at its opposite end with a discharge opening, said receiver being arranged when in one position to permit textile articles to be stacked therein and swingable to another position to effect discharge of the stacked articles through said opening, a catch mechanism for releasably holding said receiver in receiving position, an electrically controlled device for operating said catch mechanism, a ratchet disk and a pawl for operating said disk step-by-step, a circuit for said device, including a contact carried by said disk and a plurality of contacts on said support in spaced relation about the path of movement of the contact on said disk and each arranged to be engaged by the contact on said disk to complete the circuit to said device whereby the latter releases said catch mechanism, means controlled by the delivery of each article into said receiver for operating said pawl, means controlled by the movement of said receiver to its discharge position, for breaking the circuit

closed by said contacts, and separate means, actuated by said pawl operating means, for restoring said circuit breaking means to non-circuit breaking position.

14. In apparatus of the class described, the combination with a support, of a receiver to which textile articles are successively delivered into stacked relation and formed at one end with an opening through which the stack of articles is discharged, said receiver being truncated adjacent its opposite one end on said support, means on one or more walls of said receiver adapted to removably hold a container in

operative relation to said opening, a mechanism for releasably holding said receiver in receiving position, means operated by the delivery of each article into said receiver to release said mechanism when a predetermined number of articles have been stacked therein, to permit swinging of said receiver to its discharging position, and a presser mounted on said receiver adjacent its discharge opening for engaging the stacked articles as they are discharged into said container.

GLENN L. ANDERSON.
